UNITED STATES PATENT OFFICE

159,113

COMBINED STRAW AND NAPKIN HOLDER

Earl J. Weaver, Jr., Coral Gables, Fla.

Application December 6, 1948, Serial No. 150,006

Term of patent 7 years

(Cl. D44—24)

To all whom it may concern:

Be it known that I, Earl J. Weaver, Jr., a citizen of the United States, residing at Coral Gables, in the county of Dade and State of Florida, have invented a new, original, and ornamental Design for a Combined Straw and Napkin Holder, of which the following is a specification, reference being had to the accompanying drawing, forming part thereof.

Figure 1 is a perspective view of a combined straw and napkin holder, showing my new design; and

Figures 2 and 3 are end elevational views thereof.

I claim:

The ornamental design for a combined straw and napkin holder, as shown.

EARL J. WEAVER, JR.
